US00D873063S

(12) United States Design Patent (10) Patent No.: US D873,063 S
(45) Date of Patent: * Jan. 21, 2020

(54) OVEN

(71) Applicant: MIDEA GROUP CO., LTD.,
Guangdong (CN)

(72) Inventors: Ling Zeng, Guangdong (CN); Pierce James Barnard, Guangdong (CN);
Xifeng Kuang, Guangdong (CN)

(73) Assignee: MIDEA GROUP CO., LTD., Foshan,
Guangdong (CN)

() Term: 15 Years

(21) Appl. No.: 35/505,378

(22) Filed: Apr. 13, 2018

(80) Hague Agreement Data

Int. Filing Date: Apr. 13, 2018

Int. Reg. No.: DM/101957

Int. Reg. Date: Apr. 13, 2018

Int. Reg. Pub. Date: Jul. 27, 2018

(30) Foreign Application Priority Data

Nov. 1, 2017 (CN) 2017 3 0531649

(51) LOC (12) Cl. 07-02

(52) U.S. Cl.

USPC D7/350.1

(58) Field of Classification Search

USPC D7/350.1-351, 402-403, 405, 354
CPC . H05B 6/64; H05B 6/12; H05B 6/806; H05B

6/6426; H05B 6/6414; A21B 1/52

See application file for complete search history.

Primary Examiner — Mary Ann Calabrese

Assistant Examiner — Jennifer L Rempfer

(74) Attorney, Agent, or Firm — Morgan, Lewis & Bockius LLP

(57) CLAIM

The ornamental design for oven, as shown and described.

DESCRIPTION

The patent or application file contains at least one drawing executed in color. Copies of this patent or patent application publication with color drawing(s) will be provided by the Office upon request and payment of the necessary fee.

1. Oven

1.1 : Front

1.2 : Back

1.3 : Left

1.4 : Right

1.5 : Top

1.6 : Bottom

1.7 : Perspective

1.8 perspective view in an open state of use

1 Claim, 16 Drawing Sheets
(14 of 16 Drawing Sheet(s) Filed in Color)
